[57] CLAIM

The ornamental design for a fairing for motorcycles, as
shown and described.

DESCRIPTION

FIG. 1 is a perspective view taken from in front and
toward the left of the fairing for motorcycles embodying
our novel design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a rear end elevational view thereof.
